United States Patent Office

THOMAS H. SAVERY, OF WILMINGTON, DELAWARE.

Letters Patent No. 78,763, dated June 9, 1868.

IMPROVEMENT IN EXPANDING-PULLEY.

The Schedule referred to in these Letters Patent and making part of the same.

TO ALL WHOM IT MAY CONCERN:

Be it known that I, THOMAS H. SAVERY, of Wilmington, in the county of New Castle, and State of Delaware, have invented a new and improved Expanding-Pulley; and I do hereby declare that the following is a full, clear, and exact description thereof, which will enable others skilled in the art to make and use the same, reference being had to the accompanying drawings, forming part of this specification.

Figure 1 is a side view of my improved expanding-pulley.

Figure 2 is a section of the same, through the line $z z$ of fig. 1.

Figure 3 is a detail view of the scroll-disk and one rim, showing the manner in which the teeth of the arm engage with the spiral scroll of the disk.

Similar letters of reference indicate corresponding parts.

The object of this invention is to increase or lessen the velocity of machinery driven by a belt and pulley, which is accomplished by expanding or contracting the rim of the driving-pulley, so as to increase or lessen the angular velocity of the said rim with a given velocity of the shaft bearing the pulley.

This invention is designed more particularly for regulating the speed of "cooch" or "calender"-rolls of paper-mill machinery, the speed of which rolls it is desirable to regulate by some convenient and expeditious manner while the rolls are in motion.

This I accomplish by means of an expanding-pulley, the sectional rims of which are thrown out or drawn in radially by means of a spiral or scroll slot in the face of a disk, which latter revolves on the shaft of the pulley, and is engaged by corresponding teeth on the proximate face of the arms, forming part of the sectional rims composing the rim of the pulley.

The scroll-disk is connected, by a suitable train of toothed or friction-wheels, with a hand-wheel, having free motion on the shaft of the pulley, and by holding this hand-wheel from revolving with the pulley, the rims are expanded or contracted according to the direction in which the pulley is rotating.

The train of gear-wheels, connecting the scroll-disk with the hand-wheel, may be variously modified without affecting the same general result; but I will set forth a simple and effective manner by which the hand-wheel and scroll-disk may be connected to accomplish the perfect working of the invention.

The hand-wheel E is fitted with easy contact on the shaft D of the pulley, and the hub of the hand-wheel is produced and formed into a pinion, a, or the said pinion may be made separately and affixed to the hub.

The pinion a engages with a toothed wheel, b, the arbor, e, of which bears a pinion, d, which, in turn, engages with the toothed periphery of the scroll-disk A, which latter revolves freely on the shaft D. The arbor e of the wheel b, and pinion d, has a bearing in the flange-plate G of the hub of the pulley, and this bearing is continued through the sector-blocks, which are spaced apart around the face of the hub-flange, and thus form the radial slots, in which the arms B of the sectional rims C work. These slots, however, may, in practice, be planed into a hub-flange, cast originally of sufficient thickness for that purpose.

The arms B fit with finished contact within the said slots, and slide in the same as the rims C are expanded or contracted. This expansive and contractile movement is accomplished by means of teeth, formed on or affixed to the faces of the arms, and which work with easy contact in the spiral slot or scroll formed in the proximate face of the disk A, as shown at f in fig. 1, but better shown at the detail view of fig. 3.

A fillet or annular plate H is affixed to the hub-flange, and this serves to enclose the arms in their respective slots. The pinion d is located in a circular recess, formed in the plate H, the said recess opening inwardly toward the centre of the pulley, thereby permitting the engagement of the pinion with the disk.

This recess is shown partially dotted at fig. 1. The disk A is within the plate H, and the pulley is not materially encumbered by the gear-mechanism. Parts of the hand-wheel and wheel b are broken away in fig. 1, the better to show other parts of the invention.

Having described my invention, I claim as new, and desire to secure by Letters Patent—

The expanding-rims, C, of a pulley, operated by means of a hand-wheel, E, and scroll-disk A, both working on the pulley-shaft D, and connected by any suitable train of gear-wheels, substantially as shown and described.

The above specification of my invention signed by me, this 2d day of April, 1868.
